UNITED STATES PATENT OFFICE.

ROBERT WILSON, OF MIDDLETOWN, OHIO, ASSIGNOR TO WILSON & McCALLAY, OF SAME PLACE.

TOBACCO-DRIER.

SPECIFICATION forming part of Letters Patent No. 333,985, dated January 5, 1886.

Application filed May 29, 1885. Serial No. 167,017. (No model.)

To all whom it may concern:

Be it known that I, ROBERT WILSON, a citizen of the United States, residing at Middletown, in the county of Butler and State of Ohio, have invented certain new and useful 5 Improvements in Kilns for Drying Tobacco, of which the following is a full, clear, and exact description, reference being had to the accompanying drawings, forming part of this 10 specification.

My invention relates to an improvement in tobacco-drying kilns; and it consists in such an arrangement and construction of a kiln that the tobacco is introduced and moved through the kiln in one direction, while a current of 15 hot air is passed in the opposite direction; also of devices for controlling both the tobacco and the blast of air without opening or entering the kiln, all of which will be more fully 20 set forth hereinafter.

While I use my invention for drying tobacco, I do not confine my claim to its application to that purpose alone, as it can be used for any substance desired.

25 In the accompanying drawings, Figure 1 is a sectional plan view of the kiln. Fig. 2 is a side elevation, partly in section. Fig. 3 is a sectional end view, and Fig. 4 is a sectional plan view, illustrating the mechanism for 30 transferring the car from one chamber to another; and Fig. 5 is an elevation of the blower and attendant parts.

The same letters of reference are used to indicate identical parts in all the figures.

35 A A represent the walls of the kiln, which is divided into two chambers by the partition-wall A'. This wall does not extend entirely to the rear end of the kiln, so the two chambers are connected at that end.

40 B B are doors in the front end of the kiln, through which the tobacco is introduced.

The tobacco comes from the casing-tubs, where it has been moistened with a liquid mixture for imparting sweetening and flavor 45 to it. It is then placed on racks C in such a way that the air will circulate through it from all directions. These racks are placed, one above the other, on cars or trucks E, which are run into the kiln through the doors B.

50 D D are tracks extending along the floor of the kiln, and upon which the cars run. Be-

tween the tracks, at each end of the kiln, are endless chains F, provided with sprockets or projections, which catch on lugs or any convenient projections on the under side of the 55 car. These chains (of course belts may be used) pass over sprocket-wheels G G and G'. The wheel G' is geared with another wheel, G'', by a chain or belt, which is revolved by a crank or in any other convenient way. By 60 connecting the two wheels or pulleys G'' together by a belt or chain both may be worked from one end. Where two tracks are placed in one chamber, there are two sets of sprocket-wheels G G, carrying chains F, on the same 65 shafts, and so arranged that the gearing may be shifted from one to the other by the shifting-levers X, constructed in any of the usual ways and operated by the cords H H. The cars in both chambers may be operated by one 70 crank by extending the shaft through the kiln, as shown at K, Fig. 1, if proper mechanism is used for shifting the gearing, as shown at L L, Fig. 1, which is operated by the cords L', Fig. 2. By this shifting mechanism, which may be 75 arranged and constructed in any of the well-known forms, any of the cars may be moved in the direction desired by means of the single crank on the wheels G''; or, if preferred, each chamber may be provided with independent 80 chains and gearing worked from either side. By these chains the cars are propelled from one end of the kiln to the other.

Where short chains extending only part of 85 the length of the kiln are used, as shown in the drawings, and which I prefer for economy and simplicity and ease of operation, after the car has passed beyond the reach of the front chain, it is further propelled by the car behind it. The chain at the rear end can then be used 90 to bring up one car at a time for transfer across the kiln, as will be hereinafter described. Of course, if preferred, a single propelling-chain, F, extending the entire length of the kiln, may be used.

At the rear end of the kiln, where the two 95 chambers connect, a car, E', is provided on tracks at right angles to the main tracks of the kiln, the top of which is level with main tracks, so that the car carrying the tobacco 100 can be run onto the car E'. This car E' is provided with an endless cord, e, passing over

the requisite pulleys and extending outside the walls of the kiln, by which the car can be moved back and forth across the kiln. The car E' having passed through the chamber I, in 5 the direction indicated by the solid arrows, onto the car E', it is transferred across the kiln until it comes opposite the end of chamber I'.

As the chains F cannot conveniently extend across the track of the car E', it is necessary to provide some means for starting the car into the chamber I' until it can come within the operation of the chain F'. This is done by an arm or arms, M, attached to a 5 rocking shaft, N. As the shaft N is turned by the crank or lever N', the car is pushed by the arms M into the chamber I', when it comes within reach of the projections on the chain or belt F', and is propelled through the chamber I' to the front end of the kiln, where it is taken out through the doors B' B'.

In order to dry the tobacco rapidly, hot air is admitted or forced into the kiln at the front end of chamber I', when it passes in the direction shown by the dotted arrows through chamber I' into the other chamber, and passes out at the front end of chamber I through the flue O. For this purpose I connect with the front end of the chamber I' a hot-air blower comprising a blower, T, of ordinary construction, a chamber, U, containing radiating coils, and an extension, U', as shown in Fig. 5; but I do not limit myself to any specific form of hot-air injector, as any of the well-known forms may be employed, such as a suction-fan at the other end of the device, or other equivalent mechanism. The current or draft of hot air is controlled or regulated by a damper, P, operated by a rod, P', or by cords and pulleys.

In order to prevent the escape of the hot air or the cooling of the kiln when introducing or removing the tobacco, an apron, R, is provided, extending from the top to the bottom of the kiln and back of the doors B B' a little over the length of one car or truck. This apron or curtain is usually made of canvas on strips of wood, and rolls over the roller R'. It may be made either to roll up on said roller or run on a frame along the top of the kiln, as shown at R", Fig. 2. Cords S pass over pulleys S' down in front of the doors B B', one of which is attached to each end of the apron R, so it can be pulled up or down by the man in charge of the doors. When a car is to be introduced into the kiln, the apron is rolled down so as to shut off the main part of the kiln, leaving a short space between the apron and the door. The door is then opened, a car run in, and the door closed. The apron or curtain is then rolled up and the car moved through the kiln. By this means the temperature is kept even and undisturbed by the opening and closing of the kiln.

By introducing the tobacco at one end of the kiln and moving it slowly through against a current of hot air introduced at the other end,

several very important results are obtained. The tobacco before being put into the drier has been saturated with a syrup of sugar, licorice, and other flavoring substances, after which it should be dried promptly and thoroughly. If thrust at once into a closed hot-air chamber, the drying will be sudden and unsatisfactory. The moisture thrown off by 75 evaporation remains more or less in contact with the leaf. It cannot be dried so well or thoroughly.

By introducing the tobacco at the end of the kiln opposite to the end at which the hot air 80 is introduced, (after the kiln has been in operation a short time,) the tobacco meets at first the air which has passed through the entire kiln and becomes more or less saturated with the vapor arising from the moist tobacco, 85 and is not therefore suddenly subjected to dry hot air, but is dried gradually, the air becoming more and more pure and dry as the tobacco approaches the exit. The rank vapors and impurities thrown off by evaporation, 90 instead of being held in contact with the drying tobacco, are, as it were, left behind, and not reabsorbed by the tobacco. The tobacco is too damp when first introduced to the kiln to absorb anything; hence the air laden with 95 these vapors does no harm at that point, but, on the other hand, serves, by the increased humidity of the air, to prevent the too sudden drying of the tobacco. When the tobacco reaches the door B', and is thoroughly dried 100 and ready to be taken out, it meets the perfectly-pure dry air and comes out clean and free from all rank flavors and impurities. At the same time it has been dried gradually and is well cured. By this arrangement the 105 capacity of the kiln is also greatly increased, as the kiln is never opened so as to permit the escape of the heated air or the introduction of cold atmospheric air.

A great saving of labor and time is secured, 110 as one man can operate the entire kiln from the outside, while tobacco is constantly introduced and taken out at the doors without any interruption or loss of time in waiting for a kilnful to be dried and emptied before introducing a fresh supply. Of course, when 115 more convenient, the kiln may be a single long chamber with doors at each end, instead of two chambers connected at one end; and any number of kilns arranged side by side may 120 be connected by the same shafting and operated by the same man.

In order that the hot air may circulate freely through the tobacco, it is arranged on racks C, of novel construction, consisting of slats 125 arranged parallel and held apart by spacing-blocks, there being at each corner a block of such height as to serve as a foot for the rack, the blocks and slats being held together by tie-rods extending through the blocks and slats at either end. By this construction the racks are made open at the ends as well as sides, and when introduced into the kiln, placed on cars one above the other, as shown,

the air passes between the racks from end to end, whereas with the ordinary racks, which are made solid at the ends, the air could only pass between them from side to side.

5 Having thus fully described my invention, I claim—

1. A tobacco-drying kiln comprising parallel chambers communicating at one end and provided with doors at the other, one of said chambers being provided with a hot-air-injecting mechanism, ways in each chamber, and cars upon the ways for conveying the tobacco from end to end of both chambers in a direction opposite to the direction of the air-current, and mechanism, substantially as described, for transferring the cars from the ways in one chamber to the ways in another, substantially as described. 15

2. A tobacco-drying kiln having means for closing it against the admission of cold air, ways throughout the kiln, cars upon the ways, a chain and sprocket-wheels engaging with the car to propel the same, and operated by means of a handle and shaft extending outside of the kiln, whereby the car may be moved without opening the kiln, substantially as described. 25

3. A tobacco-drying kiln comprising two or more chambers communicating with each other at one end, a hot-air blower communicating with last chamber at its outer end, means, substantially as described, for closing the chambers against the admission of cold air, tracks running longitudinally through each chamber, a car upon said tracks, mechanism in each chamber, substantially as described, for moving the car, a transfer-car moving transversely across the end of the kiln to convey the cars from one chamber to the other, and a shaft provided with projecting fingers and a handle for pushing the tobacco-carrying cars from the transfer-car upon the track in the next chamber, substantially as described. 35 40

4. A tobacco-drying kiln having one or more chambers and doors to permit entrance and exit of tobacco-carrying cars, a hot-air blower at the outlet to force a current of hot air through the kiln in a direction opposite to the movement of the tobacco, and flues and dampers to control the current of hot air, whereby the tobacco is acted upon by warmer and purer air as it passes through the kiln, substantially as described. 45 50

5. In a drying-kiln, the two parallel chambers I and I', connected at one end and having doors at the other, and provided with cars E, for carrying the tobacco, and a transfer-car, E', for moving the cars E from one chamber to the other, and mechanism, such as the lugs on the car, and the chain and sprocket-wheels connected with a handle outside of the kiln, 55 for propelling and operating the cars, substantially as described.

6. In a tobacco-drying kiln provided with two or more chambers, the cars E, provided with suitable projections or lugs, moving on ways in the chamber, in combination with the chains F, engaging with the lugs, sprocket-wheels G, G', and G'', for propelling the cars, and shifting mechanism, substantially as described, for moving the cars on either track or 70 in either direction without entering the kiln.

7. In a closed drying-kiln through which the material to be dried is passed on cars, the mechanism for starting the cars, comprising a rock-shaft, N, provided with an arm, M, to 75 impinge against the cars, and handle N', substantially as described.

ROBERT WILSON.
